UNITED STATES PATENT OFFICE.

WILLIAM MCK. MORRIS, OF YARDVILLE, AND ELIAL M. STAPLES, OF ELIZABETH, NEW JERSEY, ASSIGNORS TO WILLIAM MCK. MORRIS AND EDWIN J. MORRIS, OF YARDVILLE, NEW JERSEY.

METALLIC FRAME FOR BASKETS AND TRUCKS.

No. 828,232.

Specification of Letters Patent.

Patented Aug. 7, 1906.

Application filed November 22, 1904. Serial No. 233,917.

To all whom it may concern:

Be it known that we, WILLIAM MCK. MORRIS, a resident of Yardville, Mercer county, and ELIAL M. STAPLES, of Elizabeth, 5 Union county, New Jersey, citizens of the United States, have invented certain Improvements in Metallic Frames for Baskets and Trucks, of which the following is a specification.

Our invention relates to that class of trucks or baskets which are composed of canvas or other textile material supported by a metallic frame-work, the object of our invention being to so construct such a basket 15 or truck, and especially the supporting metallic framework thereof, as to impart to the same such strength and stiffness that it will effectually withstand the rough usage to which structures of this character are subjected in use.

In the accompanying drawings, Figure 1 is a perspective view of a truck made in accordance with our invention. Fig. 2 is a perspective view of the metallic framework of 25 said truck. Fig. 3 is an enlarged sectional view of one of the joints or fastenings whereby the bars of the metallic frame are connected together. Fig. 4 is a sectional view of one 30 views illustrating modifications of certain features of the invention, and Figs. 7 and 8 are perspective views illustrating a special construction forming part of our invention.

Referring, in the first instance, to Fig. 2 of 35 the drawings, it will be noted that the frame of the truck consists of rods or bars, those shown in the present instance being of circular cross-section, although other forms of bar may be used, if desired. The base 40 member of the frame comprises opposite longitudinal side portions 1 and elevated end portions 2, the side portions 1 being by preference provided about midway of their length with bends or crimps 3. The top 45 member of the frame comprises side portions 4 and end portions 5, and each of the top and base members of the frame consists of a single rod or bar bent to the proper form and having its meeting ends soldered, brazed, or 50 welded, or else confined in one of the clips hereinafter referred to, whereby the various members of the frame are connected to-

gether. The vertical members of the frame whereby the top and bottom members are connected together, comprise corner-bars 6 and intermediate side bars 7, although the number and location of these members of the frame may be varied, depending upon the size and shape of the truck which is to be produced. Each of the vertical members of the frame has at each end a bent portion 8, lying parallel with a portion of the top or base-frame, and these parallel portions of the various members of the frame are securely confined together by means of oblong metallic clips 9, each consisting, by preference, of a piece of seamless metal tubing embracing the two bars and confining them so tightly together as to effectually prevent displacement of the vertical members of the frame in 70 respect to the top and bottom members of the same; although, if desired, the projecting end of each portion 8 may be bent, as shown, for instance, at 8* in order to still further secure it to the clip. Extending from one end bar 75 to the other of the base portion of the frame are sheet-metal strips 10, these strips being lapped around the end bars of the base-frame and said lapped portions being suitably riveted or otherwise firmly secured together. 80 Interwoven with the longitudinal sheet-metal strips 10 are transverse sheet-metal strips 11, the two sets of strips being suitably riveted or otherwise secured together so as to constitute a platform for the support 85 of the bottom of the textile body of the basket. To prevent sagging of the central portion of this bottom-supporting structure, we provide a transverse bar 12, having vertically-bent ends, which are secured by means of 90 clips 13 to the central vertical bars 7 of the frame.

The lapped ends of the sheet-metal strips 10 may serve in place of clips 9 as a means of securing together the end portions 2 of the base-frame and the bent lower ends of the corner-bars 6, and, by preference, the bent lower ends of the said corner-bars 6 extend completely across the base-frame, the preferable method of making these elements of the frame being to bend a single bar into the desired form, so that the base connections at the ends of the frame will be continuous.

The desired snug fit of the clips 9 upon the

- bars of the frame may be secured by compression of said clips after the bars have been inserted therein; but it is preferable to make the clips in the first instance of such size that 5 the bent portions 8 of the bars of the frame will have to be forcibly driven into the same, and cannot, therefore, be dislodged without the exercise of a corresponding amount of force.
- 10 In order to stiffen the frame at a point between its top and bottom members, we provide longitudinal and transverse bracing-strips 14, preferably of wood, these strips abutting at their ends against the vertical corner-bars 15 of the frame, either as shown in Fig. 4 or as shown in Fig. 5, the strips being preferably rabbeted at the ends, as shown in Fig. 4, so as to completely inclose the corner-bar 6, the joint in either case being rendered secure by 20 means of a right-angled clip 15, which is preferably provided with a raised boss 16 at the angle in order to stiffen the same. The longitudinal strips 14 are secured to the central vertical bars 7 of the frame by means of clips 25 17, said bars 7 being preferably crimped, as at 18, for the reception of the strips 14, which are thereby prevented from being displaced vertically.
- 20 The strips 14 are preferably arranged on 30 the inside of the bars 7, as shown in Fig. 2, the clips 17 being external, although a reverse construction may be adopted if desired, as shown in Fig. 6—that is to say, the strips 14 may be on the outside of the bars 7 and 35 the clips 17 on the inside of the same, and said clips may also, if desired, be located on the inside of the textile body 22 of the basket, as also shown in said Fig. 6.
- Carried by the side portions 1 of the base- 40 frame of the truck are front, central, and rear transverse bars 19, preferably of wood, these bars being grooved on their upper surfaces for the reception of the bars 1 and being secured to said bars by means of sheet- 45 metal clips 20, as shown in Fig. 1, two of these clips being employed at each end of the central bar 19 and being disposed on each side of the crimped portion 3 of the bar 1 so as to confine the bar 19 in its proper central 50 position. In hangers depending from the bar 19 are mounted wheels 21, which provide for the ready movement of the truck.
- The textile body 22 of the basket or truck is shaped to fit snugly within the metallic 55 frame thus provided, and the end portions of said textile body are preferably provided with flaps at the bottom which overlap the end bars of the bottom frame and also the end portions of the sheet-metal supporting- 60 frame and are riveted or otherwise secured to the bottom of the basket and to said supporting-frame. The top of the textile body of the basket is lapped around the top member of the frame and is also provided, by 65 preference, with a binding-strip 23, of leather

or other appropriate material, so as to better enable this portion of the basket to resist the wear to which it is subjected.

The lower portion of the textile body of the basket is confined to the metallic frame 70 by means of an external band 24, preferably of textile material, which overlaps the bars of the said metallic frame and is secured to the body of the basket by stitches or other appropriate fastenings, the corner portions 75 of this band 24 being preferably protected by extra strips 25, as shown in Fig. 1.

Suitable handles 26, of leather or textile material, are secured to each end of the basket near the top of the same to facilitate 80 the handling of the same or the pulling of it about from place to place.

When a sliding basket or truck is desired instead of a wheeled truck, we secure to each of the lower corners of the metal frame a 85 metal shoe composed of halves 27 with upturned ends, these halves being grooved to receive the bars 1 and their bent ends and being provided with lugs 28, which after the halves have been fitted to the bars of the 90 frame are secured together by means of a transverse bolt and nut, as shown in Fig. 7. Such shoes may also be applied to bars not originally furnished with them, when such bars become worn.

Having thus described our invention, we 95 claim and desire to secure by Letters Patent—

1. A metallic framework for a basket or truck, said framework comprising an upper 100 and a lower frame of bar material, with substantially vertical connecting-bars bent at their ends into parallelism with the bars of said two frames, with clips embracing and fitting snugly to said parallel portions, the 105 whole being arranged to outline a container and said clips being placed to rigidly and permanently join together said parts, substantially as specified.

2. A metallic frame for a basket or truck, 110 said frame consisting of top and bottom members, each composed of a bar or bars and vertical members also consisting of bars having their ends bent into planes parallel with the bars of the top and bottom members of the 115 frame and lying closely alongside of said bars, and clips securing together the parallel portions of the bars of the frame, substantially as specified.

3. A metallic frame for a basket or truck, 120 said frame having bars with parallel portions side by side, said bars being secured together by an encircling clip and one of the bars being crimped for the reception of said clip, substantially as specified.

4. A framework for a basket or truck, the same including upright corner-bars and independent top and bottom frames each formed of longitudinal and transverse bars all permanently connected together to outline the bas- 130

ket or truck, longitudinal and transverse bracing-strips abutting at their ends against said corner-bars and provided with angle-clips whereby they are permanently and rigidly connected to each other and to the bars, substantially as specified.

5. A frame for a basket or truck, said frame having upright corner-bars and longitudinal and transverse bracing-strips abutting at their ends against said corner-bars, and confined thereto by angular metallic clips, substantially as specified.

6. A frame for a basket or truck, said frame having upright corner-bars and longitudinal and transverse bracing-strips abutting at their ends against said corner-bars, and rabbeted at said abutting ends so as to inclose the corner-bars substantially as specified.

20 7. A frame for a basket or truck, said frame having upright corner-bars and longitudinal and transverse bracing-strips abutting at their ends against said corner-bars, said strips having rabbeted ends which inclose the corner-bars and said rabbeted ends being provided with an external angular metallic clip, substantially as specified.

8. A metallic frame for a basket or truck, having upright bars with crimped portions 30 therein, and stiffening-strips adapted to said crimped portions of the bars and confined thereto by clips which embrace the bars, substantially as specified.

9. A metallic frame for a basket or truck 35 having a base member comprising opposite longitudinal side portions and end portions connecting the same at a level above said side portions, vertical members extending upwardly from said base portion, and a top member connected to said vertical members, said base and said top members being formed each of a single bar bent to the proper form and having its ends connected to each other, substantially as specified.

40 45 10. A metallic frame for a basket or truck having a base member comprising opposite longitudinal side portions and end portions connecting the same at a level above said

side portions, vertical members extending upwardly from said base portion, and a top 50 member connected to said vertical members, said base and said top members being formed each of a single bar bent to the proper form and having its ends connected to each other, the bar forming the bottom member having 55 its side portions bent to form crimps for the attachment of a certain number of vertical members, substantially as specified.

11. A metallic frame for a basket or truck including bottom and top horizontal members, with vertical members connecting the same, said frame having a bottom-supporting structure consisting of a platform composed of sheet-metal strips mounted upon the bottom members of the frame, and said frame 60 65 having a transverse bar supported upon certain of the vertical members thereof for carrying the central portion of the platform, substantially as specified.

12. A metallic frame for a basket or truck 70 said frame having a base member composed of bars, with vertically-split shoes inclosing said bars at the corners, and having lugs bolted together, substantially as specified.

13. A metallic frame for a basket or truck, 75 said frame having a base member composed of bars with elevated end portions, and vertically-split shoes inclosing said bars at the corners, and having upturned portions for receiving the upturned portions of the bars, 80 and lugs bolted together, substantially as specified.

In testimony whereof we have signed our names to this specification in the presence of two subscribing witnesses.
